By his Attorney *Dr. J. Adams*

UNITED STATES PATENT OFFICE.

HENRY JOSEPH ROUND, OF LONDON, ENGLAND, ASSIGNOR TO RADIO CORPORATION OF AMERICA, A CORPORATION OF DELAWARE.

WIRELESS TELEGRAPHY.

Application filed March 30, 1922, Serial No. 548,004, and in Great Britain April 7, 1921.

This invention relates to improvements in wireless telegraph and telephone systems.

According to this invention I provide a set of aerials each of which is so arranged 5 that it will automatically magnify and re-radiate waves of a particular frequency falling upon it.

By the use of such aerials short waves can be transmitted and retransmitted over a long 10 distance.

It is known that the current induced in a vertical aerial of an effective height h^1 by a current in another vertical aerial of an effective height h^2 at a distance d bears to the 15 inducing current the ratio $377 \frac{h^1}{h^2} \gamma dR$ where γ is the wave length and R is the resistance of the receiving aerial, when the distance between the aerials is such that attenuation can be neglected.

20 If therefore there be a pair of nearly vertical aerials each tuned to a wave length not much greater than the fundamental wave length, and by means of a valve set with retroaction on, say, the second of these aerials 25 the resistance be reduced to a very low value, almost equal currents can be obtained in each aerial by the induction from a supply into the first aerial alone; for instance, with two aerials each 20 metres high working at 30 a wave length 100 metres with the aerials reduced to $\frac{1}{2}$ ohm effective resistance by retroaction the currents in the two will be equal, if $377 \times 400 = 100 \times \frac{1}{2} \times d$, i. e. if d equals about 3 kilometres, and the distance 35 can be increased if the resistance be still further diminished. The second aerial will in turn induce a current back into the first one which will again in turn react on the second aerial. So that if we now apply 40 retroaction to the first aerial it will be seen that depending upon the distance between the aerials (which determines the phase of the re-induced E. M. F.) and the amount of retroaction applied to each aerial, two general 45 conditions can be arrived at.

(1) If the current in the second aerial is less than in the first and the two aerial resistances are reduced to the same figure, then,

the current in the second aerial will induce back still less in the first aerial, and so on, 50 the final currents being the sum of

$$1 + e^2 + e^4 + e^6 \dots \frac{1}{1-e}$$

55 where e is less than 1.

(2) If, however, the current induced in the second aerial be larger than in the first aerial, then obviously the whole system will react up to an oscillation limit; in other words, the slightest induction in either aerial 60 will produce this maximum current, that is to say, the system will start itself oscillating.

We are concerned here with the case where

$$\frac{1}{1-e}$$

65 is finite and the system is not self oscillatory but will respond proportionally to any induced E. M. F.

If either aerial be now altered in damping, the current in the other one will be affected, 70 more or less proportionally. As a result it is possible over short distances to bridge a gap between the telephone wire systems. 75 This is illustrated in the accompanying diagram, in which A_1 , A_2 are aerials coupled through any suitable rectifiers R_1 , R_2 , to the telephone lines T_1 , T_2 , for example, by means of antenna coupling coils B_1 , B_2 , and transformers C_1 , C_2 . The aerials A_1 , A_2 , are provided with valve sets W_1 , W_2 , by which their resistance is reduced. The valve sets 80 may comprise for example, three electrode tube feed back or retroaction circuits, in which grid coils D_1 , D_2 are coupled to coils B_1 , B_2 and feed back coils E_1 , E_2 connected to the plate and plate battery are coupled to B_1 , B_2 or D_1 , D_2 . An oscillator O of any kind is arranged to produce oscillations of 85 the transmitting frequency in one of the valve sets.

When speech arrives at T_1 the voltage applied to the rectifier R_1 varies the damping 90 of the aerial system A_1 owing to the fact that more or less of the H. F. energy in the aerial

is chopped off and absorbed in the resistance W_1 depending on the voltage impressed by the speech currents from the line T_1 . This modulates the current in the aerial, consequently the current in A_2 is also reduced and the value of the current rectified by R_2 and transferred to the line at T_2 is modulated according to the speech modulations. Similarly any speech arriving at T_2 will supply modulated current to the line at T_1 , thus giving a two-way system of telephony on the same wave length. Also for telegraphy an oscillator O_2 may be provided at each station and modulation produced by making and breaking. It is obvious that if we arrange a set or group of such stations A_1, A_2, A_3 with an oscillator at one of them only, each of them can at once speak to any other of the set or group provided the whole system is stable and does not burst into oscillations automatically. I do not limit myself to this simple system of modulation which has been given by way of illustration as any other method of varying damping or phase can be used for the purpose of modulation.

Instead of setting up a group of such stations I can arrange a chain of them (A_1, A_2, A_3) across country. At any place in the system I can then induce an E. M. F. in resonance with the system and at that place or any other place I can modulate the resulting currents as I have above described in the case of only two aerials.

Having described my invention, what I claim is:

1. The combination of two telephone wire systems having a gap and means for bridging the gap comprising a pair of aerials at the ends of the gap, each being arranged to receive waves from the other, and each having means associated therewith for causing magnification and re-radiation of waves received from the other.

2. In radio signalling systems, a pair of aerials at a considerable distance apart, and each of said aerials being arranged to receive waves from each other and having associated therewith means for reducing its apparent resistance to such a value with respect to the aerial spacing that currents in one aerial induce currents of substantially equal value in the other.

3. In radio signalling systems, a pair of spaced aerials, an oscillator at one of said aerials and retroactive means at the other aerial for amplifying the received currents of the oscillator frequency said aerials being so spaced that the currents in the second aerial may be amplified to substantial equality with the currents of the first aerial.

4. In radio signalling systems, a pair of spaced aerials, an oscillator at one of said aerials, retroactive means cooperating with

each of said aerials and said aerials being so spaced that the retroactive means substantially equalizes currents of the oscillator frequency in said aerials.

5. In radio signalling apparatus, a plurality of aerials, each of said aerials being arranged to receive waves from each other and having associated therewith means for causing magnification and re-radiation of waves received thereon from any other of said aerials, and at least one of said aerials having an oscillator associated therewith.

6. In radio signalling apparatus, a plurality of aerials, each of said aerials being arranged to receive waves from each other and having associated therewith means for causing magnification and re-radiation of waves received thereon from any other of said aerials, and at least one of said aerials having associated therewith means for modulating the currents therein.

7. In radio signalling apparatus, a plurality of aerials, each of said aerials being arranged to receive waves from each other and having associated therewith means for causing magnification and re-radiation of waves received thereon from any other of said aerials, and at least one of said aerials having associated therewith means for modulating the currents therein at speech frequencies.

8. In radio signalling systems, a plurality of aerials forming an extended chain, each of said aerials being arranged to receive waves from each other and having associated therewith means for causing magnification and re-radiation of waves received thereon from any other of said aerials, and at least one of said aerials having associated therewith means for modulating currents therein.

9. In radio signalling systems, a plurality of aerials forming an extended chain, each of said aerials being arranged to receive waves from each other and having associated therewith means for causing magnification and re-radiation of waves received therein from any other of said aerials, at least one of said aerials having associated therewith means for modulating currents therein, and at least one of said aerials having an oscillator associated therewith.

10. A radio signalling system comprising a plurality of aerials, each having retroactive means associated therewith and tuned to the same wave length, said aerials and said retroactive means being so arranged and adjusted as to cause each aerial to receive, magnify and re-radiate waves from and to each other and to substantially equalize the currents in each.

11. A radio signalling system comprising a plurality of aerials, each having retroac-

tive means associated therewith and tuned to the same wave length, said aerials and said retroactive means being so arranged and adjusted as to cause each aerial to receive, magnify and re-radiate waves from each other and to substantially equalize the currents in each, and an oscillator associated with one of said aerials and arranged to generate oscillations of a predetermined

10 frequency.

12. A radio signalling system comprising a plurality of aerials, each having retroactive means associated therewith and tuned to the same wave length, said aerials and 15 said retroactive means being so arranged and adjusted as to cause each aerial to receive, magnify and re-radiate waves from and to each other and to substantially equal-

ize the currents in each, and means for modulating the currents of the system. 20

13. In radio signalling apparatus a pair of spaced aerials, means for reducing the apparent resistance of each of said aerials to cause substantial re-radiation of received waves thereby and said aerials being so spaced that the reradiated waves from each 25 will cause cumulative effects in the other.

14. In radio signalling apparatus a pair of spaced aerials, means for reducing the apparent resistance of each of said aerials 30 to cause substantial reradiation of received waves thereby and said aerials being so spaced that the reradiated waves from each will be received by the other to successively increase the current in each.

HENRY JOSEPH ROUND.
